UNITED STATES PATENT OFFICE

168,800

BED HEADBOARD OR SIMILAR ARTICLE

Cecil Edgar May, Hollywood, Calif.

Application April 28, 1952, Serial No. 19,498

Term of patent 14 years

(Cl. D5—4)

To all whom it may concern:

Be it known that I, Cecil Edgar May, a citizen of the United States, residing at Hollywood, in the county of Los Angeles and State of California, have invented a new, original, and ornamental Design for a Bed Headboard or Similar Article, of which the following is a specification, reference being had to the accompanying drawing forming a part thereof.

Figure 3 is a rear elevation, the direction of view being indicated by the arrow 3 of Fig. 1; and

I claim:

The ornamental design for a bed headboard or similar article, substantially as shown.

CECIL EDGAR MAY.
